UNITED STATES PATENT OFFICE.

JOHN G. ROH, OF SHANESVILLE, OHIO.

DEVICE FOR INSERTING FELLIES.

SPECIFICATION forming part of Letters Patent No. 314,197, dated March 17, 1885.

Application filed April 3, 1884. (No model.)

To all whom it may concern:

Be it known that I JOHN G. ROH, of Shanesville, county of Tuscarawas, and State of Ohio, have invented a new and useful Improvement 5 in Felly-Drawers; and I do hereby declare that the following is a full, clear, and exact description of the invention, which will enable others skilled in the art to which it appertains to make and use it, reference being had 10 to the accompanying drawings forming a part thereof.

My invention relates to improvements in felly-drawers in which a screw-jack and linked arms work in conjunction; and the objects of my invention are, first, to draw any 15 segment of the felly to its place, and second to do so without denting it, as is done by the usual method. I attain these objects by means of the mechanism illustrated in the accompanying drawings, in which—

Figure 1 is a side elevation of a wheel having my invention applied. Fig. 2 is a side elevation of my invention. Fig. 3 is an edge elevation of the same, showing the two sides of the 20 device for application on the two sides of the wheel.

A is a loose bar-handle operating the screw-bar B, turning freely in a rectangular flat head, C, having the corners turned down, as shown 25 in drawings, so as not to allow the felly-segment to escape. The thread of the bar B works in the head of the fork D, to the extremity of the arms of which are attached the links E E, to which links are attached the 30 ring-loops F F.

The operation of my invention is as follows: The segment of felly is placed as nearly in position as possible, when the fork D is placed down over it, the head C resting firmly on it, then the loops F F are put over the outside 40 rings of the hub and the head C forced down by means of the screw-bar B and handle A, forcing the segment before it into its place.

I am aware that a felly-drawer is known in which a U-shaped yoke for setting over the 45 felly is used, with a chain connecting the long limb thereof to the hub on one side and a screw for passing through the yoke and bearing upon the felly to force it in place, and I do not claim such.

Having thus fully described my invention, what I claim, and desire to secure by Letters Patent of the United States, is—

The combination, with the screw B, having a handle, and the head C, secured loosely to 55 the lower end of the screw, of the fork D, screw-threaded through its head for the passage of the screw B, the connecting-links E E, and the hub-rings F F, pivoted to the limbs of the fork D so as to turn laterally away 60 from the wheel, as set forth.

In testimony that I claim the foregoing I append my signature.

JOHN G. ROH.

Witnesses:

JOHN BEACTZ,
VALENTINE D. YODE.
